UNITED STATES PATENT OFFICE.

SAMUEL M. FURMAN, OF HENDERSON, KENTUCKY.

HITCHING-POST.

SPECIFICATION forming part of Letters Patent No. 224,083, dated February 3, 1880.

Application filed July 1, 1879.

To all whom it may concern:

Be it known that I, SAMUEL M. FURMAN, of Henderson, in the county of Henderson and State of Kentucky, have invented a new and useful Improvement in Hitching-Posts, of which the following is a specification, reference being had to the accompanying drawings, in which—

Figure 1 is a longitudinal section of my improved hitching-post closed or lowered. Fig. 2 is a side view of the same, illustrating its use, and part being broken away to show the construction. Fig. 3 is a detail cross-section of the upper part of the outer case or box, taken on the line $x-x$ of Fig. 1.

The object of this invention is to furnish an improved hitching-post, which shall be so constructed that it may be lowered into the ground when not required for use, so as to be out of the way, which may be readily arranged for use, and which shall be simple in construction and inexpensive in manufacture.

The invention consists of a hitching-post formed of the hollow post provided with a cross-pin in its lower part, and the inclosing box or case provided with the notched and rabbeted flange upon the inner surface of its upper part; and in the combination of the hollow post provided with a cross-pin in its lower part, the inclosing box or case provided with the notched and rabbeted flange, and the chain provided with a snap-hook at its outer end and a weight at its inner end, with each other, as hereinafter fully described.

35 A represents the post, which is made hollow or tubular, and is placed within the case or box B. The middle or lower part of the hollow post A is provided with a cross-pin, a' , the ends of which project, as shown in Fig. 1.

Upon the inner surface of the case B, near its upper end, is formed a flange, b' , which is notched or grooved transversely, as shown in Fig. 3, to allow the projecting ends of the pin a' to pass it as the post A is raised and lowered. The parts of the flange b' are rabbeted upon the upper side to form seats for the ends of the pin a' . The rabbets do not extend quite to the notches or grooves in the flange b' , so that the horse, by working the post A, cannot bring the ends of the pin a' into the said notches, and thus cause the said post to drop down into the case B.

The lower end of the post A has a cross-pin, ferrule, cap, or other stop, a^3 , attached to

it, to strike against the lower side of the flange b' when the post A is raised sufficiently, and thus prevent the said post from being drawn out of the case B.

To the upper end of the post A is attached a cap, a^2 , which has a hole formed through its middle part for the passage of the chain C. The chain C has a snap-hook, c' , attached to its upper end to be sprung into the bit-ring of the head-stall, and has a light weight, c^2 , attached to its lower end, sufficient to keep the chain always taut, and to act as a stop to prevent the chain C from being drawn out of the cavity of the post A.

The upper end of the case B is provided with a hinged cap, D, to shut down over the post A and cover and protect it.

The cap D and the upper end of the case B may be provided with perforated lugs to receive a pin, a padlock, or other fastening device.

The chain C and its attachments may be omitted, if desired, and the upper end of the post A provided with a loop, knob, or other device to receive the hitch-strap of the harness; but I prefer to use the chain as being more convenient and as making the post more complete.

All the various parts of the device are designed to be made of galvanized iron to prevent corrosion.

In using the device the box or case B is designed to be sunk into the ground or pavement to, or nearly to, its upper end, so as to be out of the way when the post A is lowered and the cap D closed.

In conclusion, I refer to Patents Nos. 32,601, 69,027, 127,085, and 209,288 as showing the present state of the art; and I disclaim anything therein described.

Having thus described my invention, I claim as new and desire to secure by Letters Patent—

The combination, in a hitching-post, of the hollow post A, provided with a cross-pin, a' , in its lower part, the inclosing box or case B, provided with the notched and rabbeted flange b' , and the chain C, provided with a snap-hook, c' , at its outer end, and a weight, c^2 , at its inner end, all substantially as herein shown and described.

SAMUEL M. FURMAN.
